Primary Examiner — Lakiya G Rogers*Assistant Examiner* — Harold E Blackwell, II(74) *Attorney, Agent, or Firm* — Mark W Handley;
Handley Law Firm, PLLC(57) **CLAIM**

The ornamental design for a ragglestic for sucker rod bundles, as shown and described.

DESCRIPTION

FIG. 1 is a perspective view of a ragglestic for sucker rod bundles embodying my design;

FIG. 2 is a front view of the ragglestic for sucker rod bundles;

FIG. 3 is a rear view of the ragglestic for sucker rod bundles; fig. 4 is a right side view of the ragglestic for sucker rod bundles;

FIG. 5 is a left side view of the ragglestic for sucker rod bundles;

FIG. 6 is a top view of the ragglestic for sucker rod bundles; and,

FIG. 7 is a bottom view of the ragglestic for sucker rod bundles.

The broken lines shown in FIGS. 1, 6 and 7 illustrate a web portion which is not part of the claimed design. None of the broken-line matter forms a part of the claimed design.

1 Claim, 3 Drawing Sheets(56)
